VEHICLE OPERATED GATE

Bernice G. Hancock, St. Matthews, S. C.

Application August 2, 1954, Serial No. 447,115

2 Claims. (Cl. 39—31)

This invention relates to an automatic farm gate and 15 has for its primary object to erect an automatic selectively opened barrier across a roadway.

Another object is to cause said barrier to be automatically removed upon the approach of a vehicle toward either side thereof.

The above and other objects may be attained by employing this invention which embodies among its features a bracket mounted adjacent one side of a roadway to tilt about a horizontal axis which extends above and substantially perpendicularly across the roadway, a stop mounted beside the roadway and extending upwardly above the level of the roadway opposite the bracket, a gate mounted on the bracket to swing in response to the tilt thereof from an active position in which it extends across the roadway and engages the stop to an inactive position in which it extends substantially parallel to the roadway adjacent the bracket, yielding means anchored beneath the roadway and operatively connected to the bracket for tilting it and swinging the gate across the roadway, and means extending across the roadway and operatively connected to the bracket for tilting it against the effort of the yielding means in response to the approach of a vehicle along the roadway toward the gate to cause the gate to swing to inactive position.

Other features include platforms mounted in the path of advance of a vehicle approaching the gate to move under the influence of said vehicle, and means carried by the bracket and operatively connected to the platforms for tilting the bracket against the effort of the yielding means upon movement of the platforms and causing the gate to swing to open position.

In the drawings:

Fig. 1 is a plan view of a roadway showing it equipped with this improved farm gate.

Fig. 2 is a longitudinal sectional view taken substantially on the line 2—2 of Figure 1.

Fig. 3 is a transverse sectional view taken substantially on the line 3—3 of Fig. 1.

Fig. 4 is a transverse sectional view taken substantially on the line 4—4 of Fig. 1.

Fig. 5 is a horizontal sectional view taken substantially on the line 5—5 of Fig. 2.

Fig. 6 is a fragmentary perspective view of the gate post, tilting bracket and gate.

Fig. 7 is a view similar to Fig. 1, parts being omitted showing diagrammatically a gate latch arrangement, and

Fig. 8 is a view taken on line 8—8 of Fig. 7 looking in the direction of the arrows and showing the latch with trip cable.

Referring to the drawings in detail, a roadway designated generally 10 is provided with a walled pit 12 of a width slightly greater than the width of the roadway. Mounted beside the roadway and extending vertically upwardly from the roadway substantially midway between opposite ends of the pit 12 is a gate post 14 carrying intermediate its upper and lower ends a pivot 16. A bracket designated generally 18 comprising a body 20

2

is mounted substantially midway between opposite ends on the pivot 16 to tilt about a substantially horizontal axis which extends above and substantially perpendicular across the pit 12. Carried by the body 20 and extending outwardly therefrom toward the roadway adjacent opposite ends of the body 20 are ears 22 and 24 through which extend axially aligned openings. An extension 26 is carried by the body 20 and extends downwardly therefrom adjacent the ear 24 and said extension is provided with 10 an opening 28 for a purpose to be more fully hereinafter described.

Mounted for rotation in the aligned openings in the ears 22 and 24 are aligned trunnions 30 comprising extensions of an upwardly extending frame member 32 of a farm gate designated generally 34. Mounted adjacent the side of the roadway 10 remote from the post 14 and extending upwardly opposite said post is a stop 36 against which the gate 34 rests when it is in active position.

Mounted in the pit 12 and extending longitudinally 20 therethrough adjacent opposite sides thereof are bed rails 38 to which are pivoted as at 40 adjacent one end of the pit 12 upwardly extending links 42. Similar links 44 are pivoted as at 46 to the bed rails 38 intermediate the ends of the pit and pivotally connected as at 48 and 50 to the links 42 and 44 respectively are the side rails 52 of a tread designated generally 54. Longitudinally spaced cross members 56 are carried by the side rails 52 and extend transversely across the tops thereof to define the tread surface of the tread 54. One of the cross members 56 is provided with an extension 58 which projects laterally beyond the tread 54 and has connected thereto one end of a rigid link 60, the opposite end of which is extended through the opening 28 in the extension 26 so that as the tread 54 moves longitudinally of the bed rails 38 the bracket 18 will be tilted about the horizontal axis previously referred to.

Pivotally connected as at 62 to the bed rails 38 adjacent the end of the pit 12 remote from the links 42 are links 64 which extend upwardly from the bed rails 40 and are pivotally connected as at 65 to the side rails 68 of a tread designated generally 70. Lever arms 72 are pivotally connected intermediate their ends as at 74 to the bed rails 38 intermediate the ends thereof and said lever arms are pivotally connected adjacent their upper ends to the side rails 68 to cooperate with the links 64 in supporting the tread 70 for movement longitudinally above the bed rails 38. Connected as at 76 to the lever arms 72 adjacent their lower ends are inter-connecting links 78 which extend upwardly from the lever arms 72 and are pivotally connected as at 80 to the side rails 52 of the tread 54. It will thus be seen that as the tread 70 advances toward the gate under the influence of an approaching vehicle the link 78 will move the tread 54 in the opposite direction and cause the bracket 18 to tilt in the direction indicated by the broken lines in Figure 2 to cause the gate 34 to swing under the influence of gravity away from the stop 36 and into open position as suggested by the broken lines in Figure 2.

In order to restore the gate 34 to closed position as illustrated in full lines in Figures 1, 2 and 4 retractile 60 coiled springs 82 are anchored as at 84 to the bed rails 38 and the opposite ends of said springs are connected to the lever arms 72 coincident with the connections 76 between the lever arms 72 and the interconnecting links 78. In the preferred form of the invention the gap between the adjacent ends of the treads 54 and 70 is bridged by a bridge piece 86 which is carried by the tread 70 and extends across a portion of the tread 54.

In Figure 7 the cross member 96 has one end 98 extending over the pit wall and to the end 98 there is connected one end 100 of link 102 that is pivotally mounted at 104 to any suitable support, the opposite end 106 being

pivotedly connected to one end of rod 108. To the opposite end of rod 108 there is connected a cable 110 which passes over pulley wheel 112, thence over pulley wheel 114, and then being attached to catch 116 at point 118. Catch 116 is pivotally mounted to any suitable support at point 120, and has its notched portion 122 constantly urged upward by compression spring 124. A cam surface 126 allows the bottom edge of the gate to cam the catch 116 down until the gate engages notch 122, when compression spring 124 will return the catch to its normal position, thus holding the gate open.

In use it will be evident that a vehicle approaching the gate 34 from the left as viewed in Figure 2 will cause the tread 54 to move longitudinally toward the tread 70 and downwardly a little, and the tread 70 toward tread 54 by means of the interconnecting linkage 78, 72, thus moving the treads against the effort of the springs 82, which normally just balance the treads 54 and 70 in their elevated outward positions, and transmitting such movement through the link 60 to the bracket 18. The bracket 18 will thus be tilted into the broken line position shown in Figure 2 so as to cause the gate 34 to swing under the influence of gravity to open position. Upon the passage of the vehicle through the gateway defined by the post 14 and stop 36, and over the tread 70, after clearing it, the springs 82 will return the treads to their initial positions thus causing the bracket 18 to tilt about the horizontal axis into the full line position shown in Figure 2 to cause the gate 34 to swing in a reverse direction until it extends across the roadway and engages the stop 36. Obviously the approach of a vehicle from the right as viewed in Figure 2 will cause a repeat opening of the gate through the simultaneous moving of the treads 70 and 54 toward each other.

The operation of the catch is as follows:

When the gate 34 opens as a result of the operation previously described, it swings back until its lower edge contacts the cam surface 126 of spring 124 and camming the catch 116 down until said gate clears the cam surface and seats in the recess 122. The catch 116, under tension of the spring 124, rises and locks the gate firmly in position.

As the car leaves tread 54 and engages tread 70 tread 70 moves in the opposite direction from the car, as shown by the arrow in Figs. 1 and 2. Cross member 96 having end 98 moves in the direction of the arrow, carrying with it end 100 of link 102. The other end 106 of link 102 will have an opposite movement to that of end 100 as a result of the midpoint pivot 104. Rod 108

therefore, moving in the same direction as the car, will pull cable 110 over pulley wheels 112 and 114, overcoming the tension of spring 124, and unseating the gate from notch 122. The gate 34 will then return to its closed position as shown in Fig. 1.

It is to be understood of course, that this latching means can be carried out in various ways, and applicant does not limit himself by what is shown and described in the specification and drawings, but only as defined by the appended claims.

I claim:

1. An automatic farm gate comprising a support, a bracket mounted adjacent one side of the gate to tilt about a horizontal axis which extends above and substantially perpendicularly across a roadway, a gate stop mounted beside the roadway and extending upwardly above the roadway adjacent the other side of said gate, said gate hinged in said bracket to swing in response to the tilt thereof from an active position in which it extends across the roadway and engages the stop to an inactive position in which it extends substantially parallel to the roadway adjacent the bracket, said bracket having a shaft extending horizontally from a midpoint on the gate, a bearing support having a bearing on said horizontal axis in which said shaft is rotatably mounted for tilting, a traffic actuated platform in two parts extending in opposite directions from said gate, each part being mounted on downwardly movable hinged parallel supports linked together to move said parts simultaneously toward each other and downwardly to rest on a solid foundation when either part receives a traffic load, said linkage being spring loaded to normally move said parts into suspended position, and an operative connection between said platform and said bracket tilting the latter in response to movement of said platforms upon being traffic actuated.

2. A gate as defined in claim 1, said operative connection being a rigid link extending substantially horizontally from the bottom of said bracket to the adjacent side of the platform.
